DESIGN FOR A COMBINED MESSAGE SHEET AND ENVELOPE

Frederick W. Baumgartner, Kansas City, Mo.

Application March 30, 1942, Serial No. 106,389

Term of patent 3½ years

To all whom it may concern:

Be it known that I, Frederick W. Baumgartner, a citizen of the United States, residing at Kansas City, in the county of Jackson, and State of Missouri, have invented a new, original, and ornamental Design for a Combined Message Sheet and Envelope, of which the following is a specification, reference being had to the accompanying drawing, forming a part thereof.

Fig. 1 is a plan view of a combined message sheet and envelope, showing my new design, and illustrating the same in a stretched-out condition;

Fig. 2 is a face view thereof, in the closed condition; and

Fig. 3 is a perspective view thereof, in partly closed condition.

I claim:

The ornamental design for a combined message sheet and envelope, as shown.

FREDERICK W. BAUMGARTNER.
